UNITED STATES PATENT OFFICE.

JAMES T. COWLEY, OF MINOT, MASSACHUSETTS, ASSIGNOR TO THE LAMSON COMPANY, OF BOSTON, MASSACHUSETTS, A CORPORATION OF MASSACHUSETTS.

CONVEYER SYSTEM.

Application filed November 3, 1922. Serial No. 598,876.

This invention concerns conveyer systems and relates more particularly to a system useful in unloading cargo from vessels and for conveying it directly to freight cars or 5 other land vehicles.

Bananas, which constitute an important item of present day commerce, are commonly brought in bulk, by water, to the southern ports of this country, where the bunches of 10 fruit are transferred from ship board to freight cars for rail shipment to interior and northern points. As the bunches of bananas are not wrapped in any way, but shipped as they are picked from the tree, 15 they present certain difficulties in handling not encountered in the transportation of merchandise such as is commonly shipped in bales, boxes or barrels, and with reference to which most of the usual handling mechanism 20 has heretofore been designed. Ordinarily the bananas are quite green when they arrive in port and cling with considerable tenacity to their stems, but when for any reason, as for example the occurrence of a 25 storm or engine break-down during the voyage, the ship is delayed in reaching port, the bananas may have attained such a stage of ripeness before unloading that slight blows will bruise them very seriously or cause them 30 to drop from the stem. When such overripe bananas are raised from the ship's hold by the ordinary bucket elevator or pocket conveyer and permitted to drop onto a platform or other support whence they are carried a 35 considerable distance on the backs of roustabouts to the freight car, there necessarily occurs a very series loss, not only from the dropping of the fruit from the stem, but also from the bruising and subsequent blackening 40 of the fruit remaining on the bunch. Even when the fruit is not overripe, serious damage results from this method of handling, and while by reason of the perishable nature of the fruit it is manifestly desirable 45 to make the transfer from ship to car as rapidly as possible, the ordinary mode of carrying out this operation involves so many handlings, and employs manual labor to such an extent that further loss is occasioned 50 by the delay at this point in the transit. Moreover, in the loading of cars with fruit, it frequently becomes necessary, in order, for example, that a given car may be entirely filled with a certain grade of fruit, to

select bunches from other and partly filled 55 cars and transfer them to the car in question, and as the cars may be upon different railway spurs in the freight yard and at a very considerable distance apart, such further handling involves added loss and delay. 60

While it is thus desirable to provide other means than those at present available for use in transferring the fruit from the ship's hold to the freight car, at certain ports at 65 least, it is not feasible permanently to convert the unloading elevator devices from that type adapted to the handling of general merchandise to a type especially arranged for unloading bananas, as there is always the possibility that the dock and elevating 70 means may at times be used for unloading general cargo, while in some cases, where docks are owned or controlled by the government, the regulations concerning the design of the dock facilities actually prohibit 75 the provision of a special elevator structure adapted only for handling of a single commodity.

The problem is thus complicated by the necessity of retaining the principal features 80 of the old type of unloading elevator apparatus with its facility for handling certain classes of general merchandise while at the same time providing an arrangement capable of efficiently handling bananas in bunches 85 even when the fruit is in overripe condition.

Objects of the present invention are accordingly to provide a convertible unloading elevator mechanism capable, with but slight labor and expenditure of time, of conversion 90 from one of the usual type, useful in the handling of general cargo, to one designed particularly for lifting bunches of bananas, or vice versa; to provide automatic means, including carriers for individual bunches of 95 bananas for transferring such bunches from the elevator device to the freight car door without intermediate handlings; to permit the stopping of loaded carriers at predetermined cars or their movement from car to car, whether upon the same railway spur or not, at will; to provide for the return of the empty carriers from the cars to the elevator and thence to the ship's hold; and to provide for directing the carriers, after again being loaded in the ship's hold, to the upgoing run 100 of the elevator to be lifted thereby.

While the conveyer system herein de-

scribed is designed with especial reference to the handling of bananas, it is evident that many of its features are equally well adapted for use in the handling of general merchandise, and it is contemplated that such use may be made of the present device, with or without such modifications as may from time to time be found desirable, without departing from the spirit of the present invention.

In the accompanying drawings there is illustrated a preferred arrangement of mechanical elements substantially designed for attaining the above objects and well exemplifying the structural arrangements which might undoubtedly be devised for securing the desired results.

Fig. 1 is a diagrammatic plan view of a conveyer system constructed in accordance with the present invention;

Fig. 2 is a diagrammatic side elevation partly broken away showing the conveyer system of Fig. 1;

Fig. 3 is a fragmentary vertical section partly in side elevation of the lower part of an elevator tower forming a part of the present conveyer system, the parts being shown in the position which they occupy when a hook conveyer device is being employed;

Fig. 4 is a view similar to Fig. 3 but showing the parts as arranged for use with a pocket conveyer;

Fig. 5 is a fragmentary plan view of diagrammatic character showing the junction of one of the spur tracks of the conveyer system with the main or dock-side track;

Fig. 6 is a diagrammatic horizontal section showing one of the spur tracks of the conveyer system, parts being broken away;

Fig. 7 is a diagrammatic side elevation showing the inclined track leading from the elevator to the main track;

Fig. 8 is a plan view of the devices shown in Fig. 7;

Fig. 9 is a side elevation of the end portion of one of the conveyer tracks, either the main track or a branch track;

Fig. 10 is a plan view of the devices of Fig. 9;

Fig. 11 is a plan view of the opposite end of the track shown in Fig. 9;

Fig. 12 is a side elevation of the parts shown in Fig. 11;

Fig. 13 is an end elevation viewed from the right-hand side of Fig. 11;

Fig. 14 is a vertical cross section on the line 14—14 of Fig. 11;

Fig. 15 is an end elevation and Fig. 16 a side elevation of the lower end of the extension leg of the elevator structure together with means which may if desired be employed for supporting and guiding the material to be elevated on its way to the elevator chain;

Fig. 17 is a fragmentary side elevation of one of the horizontal conveyer chains showing details of construction, together with a portion of the associated track and a trolley mounted thereon;

Fig. 18 is an end elevation, partly in vertical cross section, of the parts shown in Fig. 17;

Fig. 19 is a side elevation of a trolley device forming an element of the system, shown in the position which it occupies when supported by a hook of the elevator chain;

Fig. 20 is an end elevation of the device shown in Fig. 19;

Fig. 21 is a fragmentary side elevation of the parts shown in Fig. 19 but viewed from the opposite side and with the hook-engaging element in inoperative position;

Fig. 22 is a front elevation of a hook-carrying bar with a trolley supported upon one of its hooks, together with portions of the elevator chains to which the bar is secured (the chains being in section), and fragmentary parts of elements associated therewith;

Fig. 23 is a vertical cross section to larger scale on the line 23—23 of Fig. 22, together with fragmentary parts of other elements;

Fig. 24 is a vertical cross section on the line 24—24 of Fig. 22;

Fig. 25 is a vertical cross section on the line 25—25 of Fig. 22;

Fig. 26 is a fragmentary plan view showing details of the horizontal conveyer track and a switch device employed in connection therewith;

Fig. 27 is a side elevation showing certain of the parts illustrated in Fig. 26;

Fig. 28 is a side elevation of a modified form of switch structure;

Fig. 29 is a fragmentary, vertical cross section on a line such as 29—29 of Fig. 26;

Fig. 30 is a fragmentary side elevation looking in the direction of the arrow A in Fig. 26, the main track being omitted;

Fig. 31 is an end elevation of the device shown in Fig. 30, the main track being shown in vertical cross section;

Fig. 32 is a vertical section on the line 32—32 of Fig. 6, certain parts being omitted;

Fig. 33 is a perspective view of a belt conveyer device with associated parts for returning empty trolleys to the foot of the elevator device;

Fig. 34 is a front elevation, partly in section, of a modified form of bar employed with the elevator chains when bags or pockets are substituted for the hooks; and

Fig. 35 is a diagrammatic side elevation illustrating a portion of the elevator chain when using buckets and showing the means for dumping the pockets and for receiving the contents thereof.

Referring to the drawings the numeral 1 indicates a dock or wharf along which extend a pair of rails 3, 4 for supporting and

guiding one or more elevator towers 5. Each tower is provided with suitable wheels resting upon the tracks 3, 4 and with mechanism of well-known type (not shown), for 5 moving it longitudinally of the tracks as may be desired. A ship is indicated at S as moored to the dock for unloading. A series of railway spurs 6 lead from the main line of railway, not shown, substantially to 10 the dock-side, these spurs being arranged in more or less parallel relationship and extending generally at right angles to the track comprising the rails 3, 4. Upon these spur tracks freight cars, indicated at 7, may 15 be placed for loading. And endless horizontal conveyer track or guideway, indicated generally at 8 in Figs. 1 and 2, extends along the dock-side, and a series of branch tracks or guideways 9 diverge from the 20 dock-side track 8 and extend along in parallel relation to the several railway spurs 6. Each elevator tower is provided with a main boom 10 and preferably with an auxiliary boom 11 which supports a leg 12 25 adapted to depend into the hold of the vessel.

A vertical guideway comprising the spaced members 13, 14, Fig. 3, is arranged within the lower part of the tower and 30 serves to support and guide a frame 15 having journals 16 at its lower portion in which a shaft 17 is mounted. This shaft has a pair of sprocket wheels 18 fixed thereto. For adjusting the frame 15 in the guideway, a 35 screw threaded shaft 19 is secured thereto, and a worm wheel 20, constituting a nut engaging the shaft, serves to impart longitudinal movement to the latter, thus raising or lowering the frame 15. A pair of sprocket 40 chains 21, 22 pass around the wheels 18 and about suitable guide pulleys in the elevator tower, and out along the booms 10, 11 and the depending leg 12. The lower portion of the leg 12 is provided with suitable sprocket 45 wheels 23, 24 (Fig. 15) about which the chains 21, 22 pass. If desired, adjustable take-up wheels such as 25 may be arranged in the tower. The chains 21, 22 may engage these wheels, and may be tensioned 50 thereby in accordance with the position of the lower end of the leg 12 as the latter is raised or lowered as necessitated by the varying conditions met with during the unloading of the ship. The chains also pass 55 about sprocket wheels carried by a shaft 17^a and this shaft may be driven alternatively in either direction by a sprocket chain 17^b actuated by any suitable form or reverse drive gearing indicated generally at G. The 60 exact mode or mechanism for imparting movement to the chains 21, 22 forms no essential part of the present invention, however. As here shown the lower end of the leg 12 is provided with a pair of rail members 26, 27 upon which material to be ele-

vated by the chains may temporarily be supported in position convenient for attaching it to the up-going run of the elevator chain but in actual practice it is found that such rail members may well be dispensed with, 70 as the bunches of bananas or other material may be secured to the elevator chain more rapidly without the assistance of the rail members.

The chains 21 and 22 are furnished at 75 proper intervals (Fig. 22) with projecting lugs such as 28, 29 respectively which are adapted to engage socket openings in members 30, 31 secured to the opposite ends of a hook-carrying bar 32. This bar is preferably of angle iron and to its vertical flange a plurality of hooks are riveted. These hooks are of two kinds indicated at 80 33 and 34 respectively in Figs. 24 and 25, the hooks 34 being arranged adjacent to the outer ends of the bar, while the hooks 33, which are somewhat longer than the hooks 34, are secured to the bar at its central portion. The members 30, 31 are each provided with a cam device 35, 36 respectively, and 85 each cam device comprises the diverging side members 37, 38 and the connecting member 39. A pair of inclined rails 40, 41 (Figs. 1, 3, 7 and 23) are carried by the elevator tower, and the upper end portions of these 90 rails extend beneath and lie respectively substantially in the vertical planes of the paths of movement of the hooks 34 of the elevator chain bars as the latter approach the sprocket wheels 18 so that articles depending 95 from the hooks are caused to ride up onto the corresponding rails and move along the latter, the support thus afforded by the rails relieving the hooks of substantially all of 100 the weight of the articles. A pair of fixed 105 abutment members such as 43 are associated with the upper ends of the inclined rails 40, 41, and are so arranged as to be engaged by the advancing sides 37 of the respective 110 cam members 35, 36 as the latter move toward the sprocket wheels 18. As the cam members come in contact with the abutments, the bar to which the cam elements are secured is caused to turn on its axis, thereby tipping the hooks 34 rearwardly and 115 releasing the articles engaged thereby so that such articles are left upon the corresponding rail 40 or 41. The rails extend outwardly through the side wall of the elevator 120 tower and as here shown merge into a single rail at the point 44, this rail 45 being suitably bent and substantially merging into one run of the dock-side track 8 (Fig. 7). If preferred however, the rails 40 and 41 125 may be continued independently of each other to points of union with the track 8. This latter track comprises the in-board run 46 and the out-board run 47, the track 45 being connected with the latter. As the dock-side track structure and the tracks 130

branching therefrom are of generally similar construction, it will be necessary to describe only one of such structures in detail.

Referring particularly to Figs. 9 to 12, which may be considered to illustrate the dock-side track, and that end thereof for example which is shown at the right-hand side of Fig. 1, a suitable supporting framework is indicated at 48, 49, 50, which is constructed of angle iron and in any desired manner. The endless supporting track is carried by suitable hangers such as 51 from this frame, this track as above described having the in-board run 46 and the out-board run 47, which are united at opposite ends of the structure to form a continuous track. A shaft 52 is suitably journalled in the supporting frame and has mounted thereon a sprocket wheel 58. A bevel gear 59 is secured to the upper end of the shaft, and meshes with a pinion 60 carried by a shaft 61, actuated through intermediate connections by a motor 62 mounted upon the frame. At the opposite end of the track structure (Figs. 11 and 12) a pair of shafts 63, 64 are journalled. These shafts are provided with sprocket wheels 65, 66 arranged to turn in the same horizontal plane with the sprocket wheel 58. An endless chain 67 is trained around the sprocket wheels 58, 65 and 66 respectively, lying substantially in the vertical plane of the track throughout the entire extent of the latter. A pair of guide rails 68, 69 are arranged in a plane above the plane of the chain 67 and extend substantially parallel with the in-board run thereof, being spaced apart as indicated at 70. A similar pair of guide rails 71, 72 extend along and above the out-board run of the chain 67, also being spaced apart as at 73.

Above the plane of the guide rails just referred to a second endless supporting rail comprising the in-board run 74 and the out-board run 75 is mounted upon the supporting structure, the parallel runs of this rail being spaced apart, however, to a greater distance than the runs of the lower supporting rail. A second vertical shaft 76 is journalled in the supporting frame adjacent to the shaft 57 and a sprocket wheel 78 is mounted upon the shaft 76. A second sprocket wheel 79 is also fixed to this shaft and a sprocket chain 80 passes about the wheel 79 and about a similar sprocket wheel 81 fixed to the shaft 57. At the opposite end of the supporting structure (Fig. 11) vertical shafts 82, 83 are journalled to which sprocket wheels 84 are secured. An endless sprocket chain 86 is trained about the sprocket wheels 78 and 84 and comprises runs which lie substantially parallel with and above the upper supporting track throughout its entire extent. In a plane above the in-board run of the chain 86 a pair of guide rails 87, 88 are arranged. These rails extend

along and above the run 74 of the upper track, while similar guide rails 89, 90 extend above the run 75 of the track. As indicated in Figs. 10 and 11 the end portions of the rails of the several pairs of guide rails diverge from each other so as to provide a flaring entrance for the admission of the chain supporting brackets hereinafter described. While the branch tracks may if desired be provided with upper rails corresponding to the rails 74, 75 of the main track, it is found in practice that such upper rails and accessory parts are not necessarily associated with the branch tracks and in the accompanying drawings the branch tracks are indicated as without the upper set of rails.

The end portion of the dock-side track comprising the in-board run 46 and the out-board run 47 is illustrated in Fig. 5, together with the adjacent end portion of a branch track comprising the parallel runs 91, 92 which lie substantially in the horizontal plane of the runs 46 and 47. In this view, the in-board run 46 of the dock-side track is shown as provided with a hinged switch section 93 having an actuating bar 94 guided in suitable openings in the supporting framework, and provided with an actuating spring 95 which tends normally to hold the switch section 93 in alignment with the fixed portions of the run 46 of the track. By means of a suitable actuating device indicated diagrammatically at 96, the controlling bar 94 may be moved to swing the switch section 93 into alignment with a curved track member 97 to which a second switch section 98 is hinged at the point 99.

The switch section 98 normally lies substantially in alignment with the run 91 of the branch track, being held in this position by means of a spring 100. Referring to Figs. 26 to 31, the latter switch device is shown in detail, the track member 97 being provided with a bracket 101 while the track section 98 is provided with a bracket 102. These brackets are provided with ears having aligned openings for the reception of a pin 103 by means of which they are hinged together. The brackets 101, 102 are each also provided with outstanding arms 104 to which the opposite ends of a tension spring 106 are secured.

In Fig. 29 the rail 91 of the branch track is shown in vertical cross section, this rail being provided with a convex upper surface 107. In Fig. 30 the free extremity of the switch member 98 is shown in side elevation. This member is recessed at 108 for engagement with the adjacent face of the main rail 91. The upper part of the switch member 98 overhangs the recess 108, providing a downwardly concave shoulder at the point 109 and the upper edge of the outer end of the shouldered part of the member 98 is

- tapered substantially to a point as indicated at 110, the parts being so arranged that when the member 98 is brought into alignment with the member 91 the tapered end 110 of 5 the switch member forms a substantial continuation of the upper surface of the rail 91. The shoulder 109 normally lies in a plane slightly above that of the upper edge of the rail 91 but springs down into engagement 10 with the latter under the weight of a loaded trolley, the curved engaging surfaces providing locking means to hold the parts positively in operative position. The spring 106 normally tends to retain the parts in the 15 position shown in Fig. 26, the rail member 98, however, being permitted to swing outwardly away from the rail 91 upon the approach of a trolley moving along the rail 91 in the direction of the arrow B in Fig. 26. 20 Referring to Fig. 6, one of the branch tracks is shown, the central portion of its length being broken away, such track having the parallel runs 91, 92. The curved switch member 98 is aligned substantially 25 with the run 91 as previously described. The end portions of the track are curved as shown at 111, 112, forming a continuous track. From one or both sides, as may be desired, of such track, sidings such as 113 30 diverge, a single siding being shown in Fig. 6, while in Fig. 1 certain of the branch tracks are shown as provided with sidings connected to both runs thereof. Each siding may comprise a straight portion 114 35 lying substantially parallel with the runs 91, 92 of the branch track and closely adjacent to a railway spur 6, and also the curved portions 115. One of the portions 115 cooperates with a movable switch member 117 40 hinged at 118 to the run 92 of the branch track. This switch member 117 may be controlled by means of a bar 120 and a spring 121 in the same manner as the switch member 93 previously described. In Fig. 32 a 45 suitable means for controlling such switch members is shown as consisting of a bell crank 122 pivoted at 123 to the framework and having a slot 124 with which a pin 125 projecting from the bar 120 engages. The 50 other arm of the bell crank is connected by means of a link 126 to a lever 127 pivoted at 128 to the frame and having a handle 129 by means of which it may be manipulated. The track section 117 may, if desired, be 55 mounted as indicated in Fig. 28 wherein the branch track section 92 is shown as provided with a bracket 130, and the switch member as provided with a bracket 131, these brackets having outstanding ears 132, 133 respectively, provided with openings for the reception of a pivot pin 134. Referring again to Fig. 6, a movable switch member 135 is pivotally connected to the other end 60 115 of the siding track at the point 116 and 65 serves to connect the latter with the run 92 of the branch track. From the in-board run 92 of the branch track a curved rail section 201 provided with a switch 202 leads to the in-board run of the lower dock-side track. 70 A suitable framework extends from the in-board side of the elevator tower and serves to support shafts 136, 137 respectively Fig. 2, carrying suitable drums or rollers over which a belt conveyer 138 is trained. 75 This belt conveyer is inclined as indicated in Figs. 2 and 33, the lower end thereof lying substantially below the out-board run 75 of the upper supporting track, which may, if desired, be provided with suitable switch 80 means indicated diagrammatically at 75^a (Figs. 2 and 7) for diverting trolleys moving therealong onto the upgoing run of the conveyer belt. An inclined chute 139 extends downwardly from the upper end of 85 the conveyer belt 138, and terminates at a point adjacent to the upgoing runs of the elevator chains, where a platform 139^a is provided for an attendant. 90 The system as above described is intended 95 to employ article-supporting trolleys or wheeled carriers of the type shown in Figs. 19 to 21, inclusive. In these figures the trolley or carrier is shown as comprising a frame 140 having a hook 141 at its lower end and provided with spaced members 142, 143 between which a trolley wheel 144 is journalled. This trolley wheel is provided with a grooved rim adapted to fit over the curved upper edge 107 of the rails above described. 100 The upper portion of the frame 140 is provided with an upstanding ear 145 having a substantially vertical abutment surface 146. The ear 145 is also furnished with a transverse journal opening 147 in which a loop or bail 148 is mounted. This loop, when in operative position, stands vertically as shown in Figs. 19 and 20 but when inoperative falls freely into the position shown in Figs. 17 and 21 where it rests against stop 105 members 149 projecting from opposite sides of the frame 140. Each of the endless sprocket chains 67 and 86, which are of like construction, is furnished at intervals with links having brackets 150 (Figs. 17, 18) provided with transverse journal openings for a shaft 151, upon opposite ends of which rollers 152 are mounted. These rollers engage the upper surfaces of the guide rails associated with the respective longitudinal runs of the chain, and thus serve to support the chain intermediate the sprockets. Certain links of the chain, as for example those which carry the brackets 150, are also provided with depending brackets 153, which 110 cooperate with the abutment surfaces 146 of the trolleys and serve to push the trolleys along the endless rails forming the dock-side 115 and branch tracks of the system. 120 Referring to Figs. 4, 34 and 35 a somewhat 125 130

modified arrangement is illustrated. The elevator chains 21 and 22 are shown as provided with lugs 28 and 29 (Fig. 34) in the same manner as previously described, but in place of the bar 32 carrying the hooks 33, 34 a rod 154 is employed. This rod has bracket members 155, 156 at its opposite ends provided with socket openings for the reception of the lugs 28 and 29. The bars 154 serve as supports for bags, pockets, or buckets 157 formed from canvas or other suitable material and comprising loose loops whose ends are secured to adjacent bars 154 and whose intermediate portions hang loosely between the bars forming pockets or buckets for the reception of material to be elevated. As shown in Fig. 35 the direction of elevator chain 21 is as indicated by the arrow X, and for automatically dumping the contents of the bags or pockets formed by the loops 157, a roller 158 is provided, such roller being mounted upon a rock lever structure 159 preferably supported upon the shaft 17. The free extremity of this lever structure or rocker arm is normally held in the position shown in Fig. 5 by means of a flexible connection 161 secured to the lever adjacent to its free extremity and having its opposite end attached to a tension spring 162 secured to a fixed support 163. The shaft upon which the roller 158 is mounted is supported in open bearings in blocks such as 164 mounted adjacent to the free extremity of the lever device 159, and is secured in position in its bearings by means of hook members 165 carried by rods 166 passing through openings in the lever device and normally held downward by springs 167. As thus arranged the hook members 165 may be raised and the roller 158 removed, when desired. With the parts as thus described the loaded bags or pockets in moving downwardly with the elevator chain come into contact with the roller 158 and are thus turned inside out thereby dumping the contents therefrom. The resilient support for the dumping roll serves in large measure to prevent injury to the contents of the pocket, even though the article being conveyed be of a nature such that it might easily be injured by contact with fixed parts. For receiving the contents of the pockets 157, a suitable spring-supported bed 168 is preferably provided. This bed is carried at the end of a leaf spring 169 mounted upon a suitable support 170. This support is preferably of portable character, consisting of a framework mounted upon wheels and this framework also serves to support an endless belt conveyer 171 whereby articles, as indicated at 172 in broken lines in Fig. 35, may be received from the bed 168 and conveyed to a desired point outside the elevator structure.

Referring to Fig. 4 the lower part of the elevator tower is shown as arranged for use

with the modified form of elevator device just referred to. In this view, the frame 15 is shown as moved downwardly to a point below that at which it is shown in Fig. 3, so as to bring the sprocket wheels 18 below the level of the track 40 and into a position adjacent to the dumping device comprising the roll 158. When using this latter arrangement the elevator chain travels in the direction shown by the arrow X in Figs. 4 and 35, while when the hook supporting bars are employed with the elevator chain the latter moves in the opposite direction as indicated by the arrow Z in Fig. 3, any suitable reverse drive mechanism (Fig. 1) being employed for moving the chains.

Referring first to the structure as shown in Figs. 2 to 33 inclusive, it being assumed that the ship S is moored at the dock and that freight cars are located on the railway spurs and adjacent to sidings 113 of the several branch tracks of the conveyer system, the elevator tower is moved to a position opposite one of the cargo hatchways of the ship and the booms 10, 11 together with the leg 12 are so positioned as to bring the lower end of the leg within the hold of the ship and at the level of the cargo. Assuming for example that the ship is loaded with bananas, each bunch of bananas is provided with a loop of cord, wire or suitable hook, as may be desired, by which it is suspended from the hook 141 of one of the trolley devices. The loaded trolleys may be placed upon one of the rails 26, 27 in readiness to be lifted by the elevator chain. The elevator chain moves in the direction indicated by the arrow X in Fig. 16, and the loaded trolley is pushed forward toward the end of the track 26 or 27 until it is brought beneath and in the vertical plane of one of the hooks 34 of the chain. The tracks 26, 27 are preferably so positioned that the hooks 34 may automatically engage the loops or bails 198 of the trolleys, thereby picking up the loaded trolleys and lifting them from the tracks upon which they are supported. If, however, it be so desired, the tracks 26, 27 may be dispensed with and the loaded trolleys may be hooked directly onto the hooks 34 by the workman. The loaded trolley is now lifted by the elevator chain and carried upwardly along the depending leg and the booms 11 and 10 and into the elevator tower. As the hook bar 32 carrying the loaded trolley approaches the sprocket wheels 18, the cam surfaces 37 engage the abutments 43 and tip the hook bar causing the hooks 34 to swing rearwardly and to release the loaded trolleys, the wheels of which then rest upon one or the other of the rails 40 or 41 as the case may be. Due to the inclination of the rails, the trolleys slide with their loads toward the lower and inboard ends of the rails. If the rails 40 and 41

merge at the point 44, a workman will be stationed at this point to prevent interference between the loaded trolleys as they pass out onto the single rail 45. The loaded trolleys travel by gravity or under momentum onto the out-board run 47 of the supporting rail of the dock-side track and may come to rest temporarily upon this track but are soon picked up by the corresponding run of the chain 67, a depending lug 153 of which comes into contact with the abutment surface 146 of a waiting trolley, the bail 148 of the latter having dropped at this time to the position shown in Fig. 21. The loaded trolley is thus caused to travel along the out-board run of the dock-side track and around the left-hand end thereof as viewed in Fig. 1, thence moving along the in-board run of the track. As the loaded trolley moves along the in-board run 46 of the dock-side track, it will be diverted by the first operatively set switch member 93 which it encounters and caused to pass onto one of the branch tracks. If for example the switch member 93 of the first of the branch tracks is so set, the loaded trolley will move laterally onto the run 91 of such first branch track and will travel along the latter in the direction of the arrow K (Fig. 1). If the switch member 117 for the first of the sidings 113 of such first branch track is properly set, the loaded trolley will pass under its own momentum onto such siding and will stop adjacent to the freight car F. If, however, the switch 117 for the first siding 113 were not set to divert the trolley, the latter would continue to move along the branch track until switched onto a subsequent siding. If for any reason it should be desired to cause such loaded trolley, after passing entirely around the first branch track to move onto another branch track, it may again be diverted onto the dock-side track by means of the switch device 202. It is thus possible by manipulation of the proper switches to cause loaded trolleys to move continuously from the ship's hold onto any of the branch tracks of the system, and if desired to cause the loaded trolley after inspection of the bunch of bananas carried thereby to return onto the dock-side track for transmission to another branch track if desired. After the loaded trolley has been deposited upon one of the sidings and has come to rest, the workman may remove the bunch of bananas and place it in the freight car. The empty trolleys may be removed from the siding track and after several have been accumulated they are hung upon the hook of a trolley resting upon the track and this trolley with its load is pushed off from the siding onto the branch track and is carried to the junction of the latter with the main track. Here it is preferably lifted off the lower rail and placed upon the corresponding upper rail 74 for transmission to the elevator tower. When it reaches a point adjacent to the belt conveyer 138, it is switched at the point 75^a from the out-board run of the dock-side track and drops onto the conveyer belt 138 ⁷⁰ by which it is raised and dumped into the chute 139. It then slides onto the platform 139^a from which an operator may remove it and hang it upon one of the hooks 33 of the hook bar of the elevator chain. The empty trolley is then carried by the elevator chain out over the boom and down into the ship's hold where it is removed for receiving a new load. The operation of unloading bananas from a ship's hold and transferring them to the freight car is thus performed in an automatic manner with but two handlings, namely, that required for attaching it to the trolley hook in the ship's hold and for removing it from the trolley hook at the door of the freight car. The bunches of bananas, during their entire course of travel, hang free from contact with any object which might bruise or otherwise injure them, so that they arrive at the freight car door in ⁸⁰ substantially as good condition as when removed from the ship's hold. If after the unloading of the cargo of bananas the same dock facilities should be desired for use in unloading other materials, such for example as bags of grain, the hook bars 32 may be removed from the elevator chains by springing the chains 21, 22, apart sufficiently to remove the lugs 28, 29 from the sockets in the bars, and bars 154 may then be substituted ⁸⁵ for the hook bars 32. The bars 154 with their canvas loops 157 provide suitable elevator means for handling such articles as bags of grain and the like. In making the change it is desirable, however, to move the ⁹⁰ driving sprockets 18 for the elevator chain downwardly to the position shown in Fig. 3, permitting the unloading of the material from the elevator chain at a point more convenient for transfer to trucks or other conveyances. It is also desirable to drive the elevator chain in a direction opposite to that at which it moves when employing the hook bars, any desired type of reverse drive mechanism being useful for the purpose. As the ⁹⁵ loaded loops move downwardly they are turned inside out by contact with the roll 158 which is properly positioned for this purpose and are caused to fall upon the resiliently supported bed 168, from hence they are delivered to the endless belt 171 by means of which they are carried to the desired point. It is thus evident that the structure is capable of conversion without substantial labor from one which is specially adapted ¹⁰⁰ for the handling of bananas to one which is capable of handling certain classes of general merchandise and that the same elevator structure is useful in either case. In Fig. 1 several elevator structures have been shown ¹⁰⁵ ¹¹⁰ ¹¹⁵ ¹²⁰ ¹²⁵ ¹³⁰

as mounted upon the track comprising the rails 3, 4, each of these elevator structures being of similar construction and delivering to the out-board rail of the dock-side track.

Having thus described the invention, what I claim and desire to secure by Letters Patent of the United States is:

1. Apparatus of the class described comprising a wheeled trolley provided with means upon which a bunch of bananas may be freely suspended by its stem, an elevator comprising a continuous chain extending into the hold of a ship and provided with means for lifting loaded trolleys, a substantially horizontal guideway means for moving said elevator alongside the guideway, and means for transferring the loaded trolleys from the elevator device to the adjacent portion of the guideway while keeping the bunches of bananas free of contact with objects capable of injuring them.
2. In combination with a dock, elevator means supported on and movable along said dock and comprising an endless constantly moving chain adapted to extend into the hold of a ship at the dock side, hooks carried by the chain for supporting carriers from which bunches of bananas are freely suspended by their stems, means for moving the chain so as to lift said carriers out of the hold of the ship, a plurality of railway tracks upon the docks, a guideway for carriers substantially parallel to the path of movement of said elevator along the dock, means for transferring loaded carriers from the elevator to the guideway, and means for moving the loaded carrier along the guideway to a car standing upon one of said tracks.
3. A conveyer system comprising an unloading elevator having a continuously moving endless lifting conveyer, a guideway along which such elevator may move bodily, an endless track having one run thereof arranged substantially parallel to the guideway and constructed and arranged to receive articles from the elevator conveyer in all positions of the elevator, a track extending at an angle to said endless track, and means for diverting articles moving along the endless track onto such angularly disposed track.
4. A conveyer system comprising an elevator structure movable along a fixed guideway, means within said structure for elevating wheeled article carriers, an endless track extending parallel to said guideway, means arranged to receive carriers from the elevator in all positions of the latter, and branch tracks extending angularly from said endless track.
5. A conveyer system for unloading freight from vessels comprising an endless guideway extending along the dock side,

means for moving merchandise along the guideway, an elevator comprising an endless continuously moving conveyer for raising merchandise from a vessel, and means movable to points alongside various parts of the vessel and adjacent said guideway, for receiving such merchandise from the elevator and for depositing it upon the outer run of the guideway.

6. A conveyer system for use in transferring merchandise from vessels to freight cars comprising an endless track extending along the dock side, elevator means for lifting loaded, wheeled trolleys from a vessel and delivering them upon the outboard run of said track, means movable along the dock and adjacent said track for moving such loaded trolleys along said track and onto the inboard run thereof, a track diverging from such inboard run and extending substantially parallel to a railway spur, and means for diverting loaded trolleys from the inboard run of the dock side track onto said diverging track.

7. A conveyer system for unloading freight from vessels comprising an endless track extending substantially parallel to the dock side, an endless chain associated with said track for moving articles along it, a plurality of elevators for lifting articles from vessels for delivery onto the dock side track, a track diverging from the dock side track, constantly moving means for moving articles therealong, and means for diverting articles from the dock-side track onto the diverging track.

8. A freight-handling conveyer system of the class described comprising an endless track extending along a dock-side, a plurality of elevator structures arranged for bodily movement in a path substantially parallel to said track and between the same and the dock-side, means carried by each of said elevator structures for raising articles from a vessel for delivery upon the outboard run of said track, power driven, constantly moving means for moving articles along said track and onto the inboard run thereof, and means for selectively diverting articles from the latter run onto a track diverging therefrom.

9. A conveyer system comprising an endless guideway, a second endless guideway diverging from said first guideway, endless chains associated with the respective guideways and normally operative to cause articles resting upon the respective guideways to circulate continuously thereabout, and means for determining the diversion of a carrier moving along one of said guideways to the other.

10. A conveyer system comprising a plurality of elongate, endless guideways, endless chains associated with the respective guideways for moving articles therealong, an end-

- less guideway connecting all of said guideways, means for moving articles along said connecting guideway, and switch means for determining the transfer of articles from one of said guideways to another.
11. A conveyer system useful in freight yards having a plurality of railway spurs comprising elongate endless guideways substantially paralleling the several spurs, an endless guideway extending crosswise of the several guideways first named and from which the latter all diverge, an endless chain associated with each of such guideways for moving articles thereon, and switch means for selectively determining the divergence of articles from one of said guideways or their continued circulation about any particular guideway.
12. A conveyer system for use in loading freight cars comprising an endless guideway generally paralleling a railway spur, an endless chain associated with said guideway and having elements for moving articles along the latter, a siding diverging from said guideway and extending into close proximity to the railway spur, and means for diverting articles moving along the guideway onto said siding to permit them to come to rest thereon out of engagement with the driving elements of the chain.
13. A conveyer system for use in loading freight cars comprising an endless track generally paralleling a railway spur, an endless chain arranged above and parallel to the track and having depending driving lugs for moving articles along the track, a siding diverging from the track and extending parallel to the railway spur and between the latter and the adjacent run of the track, and a manually operable switch for diverting articles moving along the track onto the siding and out of engagement with said driving lugs.
14. A conveyer system for transferring merchandise from vessels to freight cars comprising an elevator arranged for bodily movement along a dock side, an endless track extending parallel with the dock side, a plurality of elongate track loops diverging from the dock side track and extending substantially parallel to corresponding railway spurs, sidings diverging from each of said track loops, means for delivering articles from the elevator to the dock side track, means for selectively diverting articles from such track to one of the track loops, and means for diverting articles from such loop onto a siding.
15. A conveyer system comprising an elevator and a substantially horizontal track for wheeled carriers, said track having a fixed rail provided with an upper surface of substantially semi-circular curvature, and a switch device comprising a pivoted rail section the free end of which is provided with an overhanging shoulder engageable with the upper surface of the fixed rail.
16. A conveyer system comprising an elevator and having a track for supporting wheeled carriers raised by the elevator, said track having a rail provided with a convex upper surface, and a switch device comprising a pivoted rail section the free end of which is provided with an overhanging shoulder for engagement with the upper surface of the fixed rail, the upper surface of the movable section being inclined toward its extremity whereby such upper surface may merge gradually into the upper surface of the rail.
17. A conveyer system comprising a normally stationary elevator device comprising a continuous constantly moving conveyer, an endless track for receiving articles from the elevator, and a second endless track substantially parallel to said first track for guiding and supporting articles to be delivered to the elevator, said tracks being so juxtaposed that articles may be transferred directly from one to the other.
18. A conveyer system comprising an endless chain elevator, a pair of substantially parallel endless tracks, one of said tracks being above the other, means for delivering articles from the elevator onto the lower of said tracks, and means for receiving articles from the other track for engagement with the elevator to be lifted thereby.
19. A conveyer system comprising an elevator structure, means for guiding said structure for bodily horizontal movement, a fixed endless guideway, means within said elevator structure for raising articles and for delivering them to said fixed guideway, a second fixed endless guideway, and means for delivering articles from said latter guideway to the elevator structure.
20. A conveyer system comprising a bodily movable elevator structure having thereon an endless series of moving supports having hooks upon which articles may be suspended and lifted, a pair of fixed superposed parallel guideways, means whereby articles may be released from hooks carried by said supports and delivered upon one of said guideways, and means for receiving articles from the other guideway and for delivering them in convenient position for attachment to hooks carried by said supports.
21. A conveyer system comprising a pair of superposed parallel guideways, means associated with each of said guideways for moving articles therealong, an elevator for lifting articles for delivery to the lowermost of said guideways, and means for receiving articles from the upper guideway and for delivering them in proximity to the elevator.
22. A conveyer system comprising a pair

of fixed guideways, an endless chain elevator, means for directing articles carried by said elevator onto one of said guideways, and an endless conveyer for receiving articles from the other guideway and for delivering them at a point adjacent to the elevator.

23. A conveyer system for use in transferring articles from vessels to freight cars comprising an elevator device for loaded article carriers, means for conveying such carriers into proximity to a freight car, a track for returning empty carriers, and an endless belt for receiving such empty carriers and for moving them into proximity to the elevator device.

24. A conveyer system for use in handling merchandise comprising an endless chain elevator for lifting loaded article carriers, a track for receiving such loaded carriers from the elevator, a second track for returning empty carriers, and an endless belt upon which such empty carriers are discharged from said second track and by which they are moved into proximity to the idle run of the elevator chain.

25. A conveyer comprising an endless chain having oppositely moving runs and means engageable with the chain for holding material of different kinds, the chain being movable in opposite directions so as alternatively to permit either run thereof to become the loaded run in accordance with the type of material being conveyed.

26. A conveyer comprising an endless chain, and means whereby supporting elements of different types may alternatively be secured to the chain, the chain being movable in opposite directions in accordance with the type of supporting element carried thereby.

27. A conveyer comprising an endless elevator chain, means whereby supporting elements of different type may alternatively be secured to said chain, and means for guiding said chain, said chain being movable alternatively in opposite directions in accordance with the type of supporting element carried thereby, and means for adjusting the guiding means.

28. A conveyer comprising an endless elevator chain, means whereby supporting elements of different type may be secured alternatively to the chain, means for causing articles carried by the supporting elements to be disengaged therefrom, and means for varying the point of disengagement of such articles in accordance with the type of supporting element employed.

29. A conveyer comprising an endless elevator chain, means whereby article supporting elements of different type alternatively may be secured thereto a guide for said chain, said guide determining the point of delivery of articles carried by the chain.

and means for varying the position of said guide in accordance with the type of supporting element employed.

30. A conveyer system comprising spaced, endless chains, and means for detachably pivotally securing the opposite ends of hook carrying bars, at intervals, to the respective chains.

31. A conveyer system comprising an endless chain, and means carried thereby permitting the alternative pivotal attachment of hook supporting and pocket carrying members.

32. A conveyer comprising an endless chain, and means whereby hook carrying or pocket carrying elements may alternatively be secured thereto, the chain being movable in opposite directions in accordance with the type of element employed.

33. A conveyer system comprising spaced, endless chains, means for driving said chains in synchronism, and means whereby hook carrying bars or pocket supporting bars may alternatively be detachably pivotally secured to said chains.

34. A conveyer system comprising a pair of spaced, endless chains, lugs projecting from each of said chains, and a series of supporting bars, each bar having a pair of socket openings for the reception respectively of a lug carried by each of the respective chains whereby the bar may be detachably secured to the chains for movement therewith.

35. A conveyer comprising a pair of spaced endless chains moving in synchronism, pivot lugs projecting in opposite directions from the respective chains, a supporting bar of a length substantially equal to the distance between the chains, said bar having axial bores in its opposite ends, and journal openings for the reception of the respective pivot lugs.

36. A conveyer comprising a pair of spaced endless chains, each chain having a series of projecting lugs, each lug of one series corresponding to an oppositely extending lug of the other series, and a series of supporting bars having axial sockets in their opposite ends for the pivotal reception respectively of a lug carried by each of the respective chains whereby such bars may be detachably connected to the chains by springing the latter apart.

37. A conveyer system comprising an endless moving chain, an article supporting hook carried thereby having a point directed in its direction of travel, and means for moving the hook to disengage the same from an article carried thereby at a predetermined point in the path of movement of the hook.

38. A conveyer system comprising an endless chain, a support with its point extending in the direction of travel thereof, pivotally secured thereto, an article carrying hook

depending from the support, and means engageable with an element of the support at a predetermined point in its path of movement with the chain for turning the support to disengage the hook from an article carried thereby.

39. A conveyer system comprising an endless chain, means for driving said chain, a hook carrying member pivotally secured thereto, a hook carried by said member, a cam secured to the member, and means engageable by said cam for rocking the member to swing the hook backwardly relative to its direction of travel.

10 40. A conveyer system comprising a chain, means for moving the chain, a hook carrying member pivotally secured to said chain and supporting a hook for movement in the direction towards which it points, a cam of 20 symmetrical contour fixed to said member, and means engageable by said cam for turning said member whereby to swing the hook to inoperative position.

15 41. A conveyer comprising a pair of endless chains, a bar extending transversely from one chain to the other, means for detachably and pivotally securing the ends of the bar to the respective chains, a hook secured to the bar, a cam member fixed to the 30 bar adjacent to one of its ends, a guide pulley beneath which the chain passes, and fixed means engageable with said cam member below its axis of rotation and at a point adjacent to said guide pulley for turning said bar whereby to release its hook from an article suspended thereon.

42. A conveyer system comprising an endless chain having provision for the alternative attachment thereto of hook supporting 40 or pocket carrying members, means co-operable with such pocket carrying members for dumping the pockets at a predetermined point, means co-operable with the hook supporting members for releasing therefrom articles supported thereby, and means for propelling said chain in opposite directions.

45 43. A conveyer system comprising an elevator chain, a pivotally supported hook supporting member carried thereby supporting a hook with its open side facing in the direction of travel of said elevator chain, said member having a cam fixed thereto, a fixed inclined supporting rail extending in the vertical plane of movement of a hook carried by said member, and means engageable with said cam at a point adjacent to the high end of the rail whereby to tip the hook carrying member to release an article engaged by the hook to permit it to move freely 55 along the rail.

44. A conveyer system comprising an elevator having means for simultaneously raising a pair of laterally spaced articles, means for simultaneously disengaging such articles 60 from the elevating means, parallel guide-

ways for receiving such articles, a guideway extending at an angle to said parallel guideways, and means whereby articles moving along said parallel guideways may be caused to pass into engagement with said 70 angularly extending guideway.

45. A conveyer system comprising an elevator having a hook carrying bar provided with a pair of hooks upon which articles may simultaneously be placed, means for 75 disengaging such articles from the respective hooks, inclined guideways for the released articles, a substantially horizontal guideway, and means for delivering articles 80 from both of the inclined guideways onto said horizontal guideway.

46. A conveyer comprising an elevator structure having an endless elevator chain therein, an inclined rail also carried by said structure and having the high end thereof 85 adjacent to a run of the chain for receiving articles therefrom, means for bodily moving the elevator structure in a given path, and a fixed rail so constructed and arranged that it may receive articles moving down said 90 inclined rail regardless of the position of the elevator structure.

47. A conveyer system comprising article elevating means, an inclined guideway along 95 which articles delivered by the elevating means may descend, means supporting the elevating means and guideway for simultaneous bodily movement, a fixed substantially horizontal guideway, and means whereby articles moving down said inclined guideway 100 may be delivered upon such horizontal guideway in all positions of the elevating means.

48. A conveyer system comprising a bodily movable elevator having means for lifting article carriers, a track having a portion 105 thereof extending substantially parallel to the path of bodily movement of the elevator, automatic means for disengaging article carriers from the elevator, means for delivering said carriers upon the track, and constantly 110 moving means for causing such carriers to travel along said track.

49. A conveyer system comprising an elevator having supporting hooks engageable with wheeled, article carrying trolleys, an 115 inclined receiving track, means for releasing trolleys from their respective supporting hooks in position for their wheels to engage said track, a track extending transversely of the lower end of said inclined track for receiving loaded trolleys therefrom, and means for moving the loaded trolleys along 120 said second track.

50. A conveyer system comprising an endless chain elevator having a hook thereon, a track, a carrier having a wheel for engagement with the track and a loop engageable by the elevator hook, means for moving the endless chain whereby to lift a carrier suspended upon its hook to the level of the 125 130

track, and automatic means for disengaging the hook from the carrier loop whereby to release the carrier therefrom with its wheel resting on the track.

51. A conveyer system comprising in combination an elevator having a supporting hook, an inclined track, a wheeled carrier having means engageable by the elevator hook whereby the carrier may be lifted to 10 the level of the upper end of the track, and means for releasing the hook from said carrier whereby to permit the latter to move downwardly along the track.

52. A conveyer system comprising in combination an endless elevator chain having a movable hook mounted thereon, an inclined track having its upper end arranged below and in the vertical plane of movement of said hook, a carrier having a bail engageable by the elevator hook whereby the carrier may be raised to a position immediately above the upper end of the track, and cam means for turning the hook whereby to disengage the carrier bail and to leave the carrier upon the track.

53. A conveyer system of the class described having guide tracks, and article carrying trolleys for use on such tracks, said trolleys each comprising a frame having an article supporting hook at its lower end, a trolley wheel at its central portion, and a suspension element adjacent to its upper end.

54. A conveyer system for transferring bananas from a vessel to freight cars comprising an elevator device having an upwardly moving hook, a track for receiving articles from the elevator, and an article carrier comprising a frame having a loop for engagement by the elevator hook, a trolley wheel engageable with the track, and means upon which the bananas may be supported.

55. A conveyer system of the class described having a guide track and driving means moving parallel to such track, and an article carrying trolley device movable along such track, said trolley comprising a frame having a trolley wheel for engagement with the track, a hook upon which an article may be suspended, and an abutment member arranged for engagement with the driving means.

56. A conveyer system of the class described having a guide track, a driving chain moving parallel thereto, and an article carrying trolley device comprising a wheel en-

gaging the track, a hook arranged below said wheel, an abutment member above said wheel for engagement by an element of the driving chain, and a bail for engagement by means for lifting the trolley device.

57. A conveyer system of the class described having a guide track, a driving chain associated therewith, and an article carrier comprising a frame having a trolley wheel engaging the track, a hook depending from the frame, an abutment member arranged above the trolley wheel for engagement by an element of the drive chain, and a pivoted bail normally below the operative portion of the abutment member but movable to position for engagement by a trolley lifting element.

58. A conveyer system for transferring bunches of bananas from a vessel to freight cars comprising an endless elevator chain having a hook secured thereto, such chain depending into the hold of the vessel, track means extending from a point adjacent to said elevator chain to a point adjacent to the freight car, a carrier having a hook upon which a bunch of bananas may be suspended, a bail engageable by the elevator hook, and a trolley wheel engageable with the track, and means whereby such carrier may be impelled along the track.

59. A conveyer system comprising a movable elevator tower, an endless track having one run thereof adjacent to said tower in all positions of the latter, endless tracks branching from the other run of said first track, an endless elevator chain within the tower, means carried thereby for lifting wheeled article carriers, means for releasing the carriers from the lifting means, means for receiving and guiding a carrier so released to the adjacent run of the first named endless track, means associated with the latter track for moving carriers along it, switch means for selectively diverting moving carriers on to a branch track, means for returning empty carriers to the elevator tower comprising tracks paralleling the first named endless tracks, means for moving carriers along such parallel track, and an endless belt conveyer for receiving the empty carriers and depositing them in close proximity to the elevator chain.

Signed by me at Syracuse, N. Y. this 30th day of September 1922.

JAMES T. COWLEY.

Certificate of Correction.

It is hereby certified that in Letters Patent No. 1,585,234, granted May 18, 1926, upon the application of James T. Cowley, of Minot, Massachusetts, for an improvement in "Conveyer Systems," an error appears in the printed specification requiring correction as follows: Page 10, lines 128 and 129, claim 38, strike out the words "with its point extending in the direction of travel thereof" and insert the same to follow after the word "support," page 11, line 1, of the same claim; and that the said Letters Patent should be read with this correction therein that the same may conform to the record of the case in the Patent Office.

Signed and sealed this 22d day of June, A. D. 1926.

[SEAL.]

M. J. MOORE,
